UNITED STATES PATENT OFFICE.

EWEN C. HENDERSON, OF NEW GLASGOW, NOVA SCOTIA, CANADA.

ENGINE.

1,094,329.

Specification of Letters Patent. Patented Apr. 21, 1914.

Application filed January 3, 1913. Serial No. 740,011.

To all whom it may concern:

Be it known that I, EWEN C. HENDERSON, a subject of the King of Great Britain, residing at New Glasgow, in the Province of Nova Scotia and Dominion of Canada, have invented new and useful Improvements in Engines, of which the following is a specification.

This invention relates to engines, the object in view being to provide an improved valve gear, especially designed for use in connection with internal combustion engines, but also applicable, as will hereinafter appear, to steam engines or any motor of the expansion type.

One of the main objects of the present invention is to provide, in connection with the intake and exhaust ports of the cylinder of the engine, a rotary cylindrical valve having ports to register with the ports of the cylinder, and in connection therewith a throttle tube which is adjustable around the valve, so as to vary the amount of fluid or gas passing to the engine.

A further object of the invention is to provide means for adjusting and holding the throttle tube, and for taking up wear between such throttle tube and the port of the cylinder in connection with which the valve is employed.

A further object of the invention is to provide a valved auxiliary air supply adapted to work in conjunction with the valve of this invention.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a vertical diametrical section through an engine cylinder, showing the intake and exhaust valve arrangement of this invention. Fig. 2 is a sectional view taken lengthwise and centrally of the intake valve. Fig. 3 is a diametrical longitudinal section through the intake valve. Fig. 4 is an end view of the valve case, showing the toothed segment. Fig. 5 is a detail section, showing the means for adjusting the take up liner. Fig. 6 is a view of the intake valve similar to Fig. 3, showing the valve provided with double the number of ports.

Referring to the drawings, 1 represents

the cylinder of an engine of the internal combustion type, in which is mounted a reciprocating piston 2. The cylinder 1 is shown as water jacketed, at 3, and provided with the usual head 4 at its upper or outer end.

In carrying out the present invention, each cylinder is provided at its opposite sides with machined flat faces 5, adapting the valve casings of this invention to be bolted or otherwise fastened rigidly thereto.

In Fig. 2, the invention is shown as applied to a two-cylinder engine, the valve being made of sufficient length to include and feed or exhaust both of said cylinders. It may be stated at this point that any number of cylinders may be employed, the valve being of a length commensurate therewith, so as to carry the gas or fluid to each and all of the cylinders, or exhaust the same therefrom, as the case may be, it being evident from Fig. 1 that the exhaust valve is arranged on one side of the cylinder or cylinders, and the intake valve on the opposite side. The intake valve 6 is in the form of a hollow cylinder or tube of suitable size, in accordance with the amount of gas or fluid required, said valve being provided at one end with a longitudinally extended journal 7, to the outer end of which is secured a bevel gear wheel 8 meshing with another bevel gear wheel 9 on the upper end of a valve actuating shaft 10 which extends downward and is geared to the crank shaft 11, as shown, so that the valve 6 is driven by the crank shaft and at a speed which will cause the ports thereof to register with the ports leading into the cylinders at the proper times.

As shown in Fig. 3, the intake valve is provided with outlet ports 12 and 13 adapted, respectively, to register with the intake ports 14 and 15 of the cylinders, as shown in Fig. 2. The valve is also provided centrally with any suitable number of longitudinally elongated ports 16, which register with the intake pipe 17 leading from the carburetor or other source of supply.

Extending around and inclosing the rotary valve 6 is a throttle tube 18 which is provided at one end with a reduced sleeve 19 extending beyond the end thereof, and fitting around the journal 7 of the valve 6, thereby forming a bearing for said journal, as clearly shown in Fig. 2. Balls 20 are inserted in grooves in the abutting ends of the valve and throttle tube, and at the opposite

end, the valve 6 and throttle tube 18 are left open and grooved in their edges to receive a circular series of anti-friction balls 21 which work against a plug 22 having screw threads 23, by which it is screwed into the end of the casing 24 which houses both the valve and the throttle tube. The plug 22 which acts as an end bearing for both the valve and the throttle tube is adjustable, by reason of its threaded connection with the valve case, thereby enabling the wear of said parts to be compensated for.

The casing 24 is secured to the machined faces 5 of the cylinders by means of cap screws 25, or their equivalent. Secured to the projecting sleeve 19 of the throttle tube 18 is a throttle lever 26 which is fast on the sleeve 19, so that by moving the lever 26 in one direction or the other, the throttle tube 18 may be turned. This throttle tube, as shown in Fig. 1, is provided with openings 27 in one side thereof, adapted to register with the outlet ports of the valve 6 and the inlet ports 28 leading into the combustion or expansion chambers of the cylinders. The throttle tube 18 is also formed with ports 27' to admit the gas to the ports 16 of the rotary valve 6. The throttle tube is provided with an opening 27 for each cylinder, as indicated by dotted lines in Fig. 2, and the openings 27 are preferably somewhat larger than the outlet ports 12 and 13 in the intake valve 6. Within each port 28 is mounted a take-up liner 29 held in place by means of a set screw 30 inserted through the valve case and impinging against said liner. This liner bears snugly against the outer surface of the throttle tube, as shown in Fig. 1, so as to prevent leakage of the gas or other fluid. As wear 40 takes place on said liner, it may be adjusted closer up to the throttle tube and held by means of the binding screw 30.

Secured to the lever 26 is a thumb latch lever 31 which is adapted to be sprung toward and away from the lever 26, said latch lever carrying a latch lip adapted to engage a toothed segment 32 on the adjacent end of the casing 24, so as to hold the throttle tube turned to any desired extent.

33 designates an auxiliary air supply pipe which leads into the valve case at a point preferably opposite the intake tube 17, above referred to, said supply pipe 33 being open to the atmosphere and being controlled by a butter-fly throttle valve 34 having a suitable lever handle 35. This provides two ways of throttling the engine, either by means of the lever 31, or the auxiliary air supply controlling lever 35. The air passing inward through the pipe 33 finds its way through the slots 16 into the interior of the rotary intake valve. The exhaust valve 36 at the opposite side of the engine is mounted to turn directly within its casing 37, there being no need at this point for the throt-

tle tube 18, which is used in connection with the intake valve. Furthermore, it is desirable to make the exhaust ports 38 of the exhaust valve larger than the corresponding ports 12 and 13 of the intake valve, in order to avoid back pressure.

While only one port is shown in Fig. 3 for each cylinder inlet port, it will be apparent that where it is desirable to revolve the intake valve more slowly, the port referred to may be duplicated at opposite sides at the intake valve, as illustrated in Fig. 6, in which event the gearing interposed between the crank shaft and the rotary valve will be correspondingly designed, in order to give the proper timing to said rotary intake valve. The same idea will, of course, apply to the exhaust valve. Furthermore, the principle referred to may be applied either to internal combustion engines of the two cycle or four cycle type.

From the foregoing description, it will be understood that by means of the lever 26 and the latch referred to, the throttle tube 18 may be turned to any desired extent, for the purpose of regulating the size of the ports leading into the cylinders. The intake valve 6 is always filled with expansive fluid passing in through the opening 16, and said fluid is fed to each cylinder when the port 12 or 13 comes into registration with the port leading into the cylinder. The ports 12 and 13 are, of course, made of such size as to supply the necessary amount of gas to the cylinder, in accordance with the rapidity of rotation of the valve, and the intake and exhaust valves are, of course, so timed as to admit and exhaust the charges of fresh and burnt gases at the proper point in the cycle of movement of the piston.

What is claimed is:

1. In an engine, the combination of a cylinder having intake and exhaust ports, of rotary intake and exhaust valves controlling said ports, each valve comprising a rotary tubular body having an opening in one side to register with the corresponding cylinder port, an oscillatory throttle tube incasing the intake valve and journaled thereon and provided with an opening to register more or less with the opening in the valve body, means for rotating the valve and timing the same with the crank shaft, means for turning and holding the throttle tube, a valve case inclosing said valve body and throttle tube, and a plug threaded into said valve case and forming an end bearing for both the valve body and the throttle tube.

2. In an engine, the combination of a cylinder having intake and exhaust ports, of rotary intake and exhaust valves controlling said ports, each valve comprising a rotary tubular body having an opening in one side to register with the corresponding cylinder port, an oscillatory throttle tube incasing

- the intake valve and journaled thereon and provided with an opening to register more or less with the opening in the valve body, means for rotating the valve and timing 5 the same with the crank shaft, means for turning and holding the throttle tube, and a valve-controlled auxiliary air supply, the valve body and throttle tube being ported to register with the main fluid inlet and the 10 auxiliary air supply.
3. In an engine, the combination of a cylinder having intake and exhaust ports, of rotary intake and exhaust valves controlling said ports, each valve comprising a rotary 15 tubular body having an opening in one side to register with the corresponding cylinder port, an oscillatory throttle tube incasing the intake valve and journaled thereon and provided with an opening to register more or less with the opening in the valve body, 20 a take up liner in the cylinder port adjustable toward and against the throttle tube, means for rotating the valve and timing the same with the crank shaft, and means for turning and holding the throttle tube. 25

In testimony whereof I affix my signature in presence of two witnesses.

EWEN C. HENDERSON.
